(57) **CLAIM**

The ornamental design for a candle jar with cap, as shown and described.

DESCRIPTION

FIG. 1 is a front, top perspective view of a candle jar with cap showing our new design therefor;

FIG. 2 is a front elevational view thereof, the rear and side elevational views being identical;

FIG. 3 is a bottom plan view thereof;

FIG. 4 is a top plan view thereof;

FIG. 5 is a view similar to FIG. 1 of another embodiment of the invention;

FIG. 6 is a front elevational view thereof, the rear and side elevational views being identical;

FIG. 7 is a bottom plan view thereof;

FIG. 8 is a top plan view thereof;

FIG. 9 is a view similar to FIG. 1 of a still further embodiment of the candle jar with cap;

FIG. 10 is a front elevational view thereof, the rear and side elevational views being identical;

FIG. 11 is a bottom plan view thereof;

FIG. 12 is a top plan view thereof;

FIG. 13 is a view similar to FIG. 1 of another embodiment of the invention;

FIG. 14 is a front elevational view thereof, the rear and side elevational views being identical;

FIG. 15 is a bottom plan view thereof; and,

FIG. 16 is a top plan view thereof.
